UNITED STATES PATENT OFFICE

GORDON E. ROEDDING, OF GRAND RAPIDS, MICHIGAN, ASSIGNOR TO GRAND RAPIDS
BRASS COMPANY, OF GRAND RAPIDS, MICHIGAN

LATCH

Application filed April 13, 1929. Serial No. 354,759.

The main objects of this invention are:

First, to provide an automatically engaging reversible latch which is easy to operate and at the same time automatically engages 5 the strike or keeper with considerable power.

Second, to provide a latch having these advantages having relatively few and simple parts.

Third, to provide a latch in which parts are 10 mounted on the base plate providing convenient assembly and also permitting the housing to be made of light material.

Fourth, to provide a latch in which the parts are very compactly arranged.

15 Objects pertaining to details and economies of my invention will definitely appear from the description to follow. The invention is defined in the claims.

A structure which embodies the features of 20 my invention is clearly illustrated in the accompanying drawing, in which:

Fig. 1 is a fragmentary elevational view 25 of a refrigerator door and casing with my improved latch and the coacting keeper mounted thereon, the housing of the latch being sectioned on line 1—1 of Fig. 3.

Fig. 2 is a fragmentary view corresponding 30 to that of Fig. 1 with the latch in retracted position.

Fig. 3 is a fragmentary view mainly in section on line 3—3 of Fig. 1.

Fig. 4 is a fragmentary view on line 4—4 of Fig. 1.

Fig. 5 is a fragmentary view looking from 35 the left of Fig. 1 illustrating the relation of the bolt to the keeper.

Fig. 6 is a perspective view of the base plate.

Fig. 7 is a perspective view of the bolt actuating lever.

In the accompanying drawing 1 represents a refrigerator housing and 2 the door thereof. My improved latch comprises a base plate 3 which constitutes the main support 45 for the operating parts. The bolt 4 is mounted on the pivot 5 for swinging and tilting movement, the pivot opening 6 of the bolt being of such size as to permit this tilting movement. The pivot is riveted or upset in 50 a hole 7 in the base plate.

At each side of this pivot and uniformly spaced relative thereto I provide fulcrum members 8. These fulcrum members in the embodiment illustrated are V-shaped and struck up from the plate. The plate is also 55 provided with slot-like detent or keeper openings 9 disposed in spaced relation relative to the longitudinal center of the plate.

The bolt actuating lever 10 is provided with oppositely projecting arms 11 which are pivotally and slidably associated with the fulcrum members, this lever being preferably formed as a sheet metal stamping and provided with flanges 12 providing fulcrum engaging surfaces of substantial width. These 65 arms 11 are shouldered at 13. The shouldered portions are cammed and coact with the fulcrum members in controlling the movement of the lever and also centering the lever between the fulcrum members when in 70 normal or central position.

The lever is provided with a laterally projecting T-shaped head 14 which engages in the longitudinal slot 15 in the lever. A coiled spring 16 is arranged within this slot with 75 one end in engagement with the head of the lever and with the other end in engagement with the end 17 of the slot, so that the lever is yieldingly urged against its fulcrum members and is normally supported in engagement with both fulcrum members as shown in Fig. 1. When the lever is swung to retracted position, for instance, as shown in Fig. 2, it 80 fulcrums on pivots on the lower fulcrum member of that figure. The opposite arm of 85 the lever swings away from its fulcrum with its cam shoulder portion in sliding engagement therewith, the shoulder dropping away quite abruptly during the latter part of the stroke so that, during this part of the stroke, 90 no additional pressure is applied to the spring.

The advantage is that as the lever is swung from its normal or central position tension 95 on the spring is increased until the bolt approaches its fully retracted position and the increasing of the tension ceases, so that the bolt under the pressure on the handpiece quickly moves to its fully retracted position, in which position the lugs 18 on the under 100

side of the bolt snap into the keepers or 50
detent slots 9. The spring acts to tilt the
bolt on its pivot at this point.

The bolt is thus retained in its retracted
position until manually released or until in
55 swinging the door to closed position the bolt
is engaged by the tappet 19 disposed above
the keeper 20. This tappet disengages the
bolt and allows it to swing into engagement
10 with the strike or keeper 20 under the action
of the spring actuated lever.

The housing 21 is adapted to engage the
base plate and the operating parts are mounted
15 thereon. To retain the housing in as-
sembled relation to the base plate and sup-
port the upper end of the pivot 5, the pivot
is preferably provided with a head 26 and
is arranged through the support 22 struck
20 inwardly from the housing in forming the
bolt opening 23. The opposite wall of the
housing is provided with an opening to per-
mit of the swinging of the lever therein.

My improved latch is very simple and eco-
nomical in structure; the parts are easily as-
25 sembed, and are compactly arranged. The
parts being assembled on the base plate, the
housing is relieved of substantially all strain,
so it may be made of relatively light gage
brass or other suitable material.

30 I have illustrated my improvements as I
have embodied them in a refrigerator latch.
I have not attempted to illustrate or describe
other embodiments or adaptations as it is
believed that this disclosure will enable those
35 skilled in the art to embody or adapt my im-
provements as may be desired.

Having thus described my invention what
I claim as new and desire to secure by Let-
ters Patent is:

40 1. In a latch, the combination with a base
plate having spaced fulcrum members struck
up therefrom, a pivot on said plate disposed
centrally relative to said fulcrum members,
a bolt mounted on said pivot, a lever pro-
45 vided with a laterally projecting head slid-
ably engaging said bolt and with oppositely
projecting arms engaging said fulcrum mem-
bers, a spring acting to urge said lever
against said fulcrum members, and a hous-
50 ing for the base plate and the parts mounted
thereon having openings in opposite walls
through which said bolt projects.

55 2. In a latch, the combination with a base
plate having spaced fulcrum members, a bolt
mounted between said fulcrum members for
swinging movement, a lever slidably engag-
ing said bolt and provided with oppositely
60 projecting arms engaging said fulcrum mem-
bers, a spring acting to urge said lever
against its said fulcrum members, and a
housing for the base plate and the parts
mounted thereon having openings in oppo-
65 site walls through which said bolt projects.

70 3. In a latch, the combination with a sup-
port provided with spaced fulcrum mem-
bers for swinging movement, a lever slidably
engaging said bolt and provided with oppo-
sitely disposed shouldered arms pivotally
75 and slidably engaging said fulcrum mem-
bers, the shoulder portions of the lever lying
between the fulcrum members when the lever
is in central position, and a spring acting
to urge said lever against said fulcrum mem-
bers.

75 4. In a latch, the combination with a sup-
port provided with spaced fulcrum members
and with spaced keepers, a bolt mounted be-
tween said fulcrum members for pivotal and
tilting movement and engageable with said
80 keepers when the bolt is in its retracted po-
sitions, a lever operatively associated with
said bolt and provided with oppositely dis-
posed arms engaging said fulcrum members,
and a spring acting to urge said lever against
85 both of said fulcrum members.

5. In a latch, the combination with a sup-
port provided with spaced fulcrum members,
a bolt pivotally mounted between said ful-
crum members, a lever operatively connected
90 to said bolt and provided with oppositely dis-
posed arms pivotally and slidably engag-
ing said fulcrum members, and a spring act-
ing to urge said lever against both of said
fulcrum members.

95 In witness whereof I have hereunto set my
hand.

GORDON E. ROEDDING.
